Filed Mar. 23, 1962, Ser. No. 181,877

9 Claims. (Cl. 244—145)

The present invention relates to a parachute. This application is drawn to a parachute of the type disclosed in the commonly assigned copending application Ser. No. 746,692 filed July 7, 1958 by Otto Brinkmann and now Patent No. 3,035,798.

In said copending application there has been disclosed a parachute with a canopy provided with numerous venting passages having funnel-shaped, upwardly constricted nozzles projecting therefrom whereby air from below the canopy, entering the relatively wide funnel mouth of each nozzle, escapes upwardly at increased speed and exerts a descent-slowing action upon the parachute.

According to the disclosure of the copending application a canopy of this type was found to be particularly advantageous when combined with a second canopy overlying the first one, this second canopy having a relatively large central aperture through which the air streaming out of the vents could escape. An object of the present invention is to extend the descent-slowing and parachute-stabilizing effect of such vents to single-canopy devices.

Another object of this invention is to provide an improved parachute of increased carrying capacity whereby it is possible to handle larger loads and/or effect slower descents with a parachute of given weight or, conversely, to reduce the weight and the size of the parachute for a prescribed rate of descent of a given load.

It has been found in accordance with the present invention, surprisingly enough, that the foregoing objects can be realized with a parachute whose single canopy when fully opened has a toroidal bulge just above its peripheral edge, the diameter of the canopy at the center of the bulge thus being somewhat greater than the diameter of said peripheral edge, and wherein the air vents or at least the greater part of such vents (in terms of combined cross-sectional area) are disposed in the region of that bulge. The canopy also has a larger, preferably adjustable air-escape aperture at its center.

Advantageously, according to another feature of the invention, the peripheral edge below the bulge is bounded by a resiliently deformable annular element, such as a rubber cord, whose presence serves to spread the rim of the canopy upon unfolding sufficiently to enable air to pass into its concavity and to open it fully.

Though the invention does not exclude the provision of additional vents at locations closer to the center of the canopy, tests have established that air passages at these locations are progressively less effective in slowing and stabilizing the parachute as their distance from the peripheral bulge increases. It is believed that the advantageous and unexpected effects of the present improvement are due to the maintenance of a constant turbulence around the bulge, with the central air passage acting mainly as the stabilizing means while the peripheral vents control the rate of descent. It has been found that pendulations, which in conventional parachutes may range between 5° and 15° and which increase with the load, are greatly reduced or almost completely eliminated thereby.

The above and other objects, features and advantages of this invention will become more fully apparent from the following detailed description of a preferred embodiment; reference being made to the accompanying drawing in which:

2

FIG. 1 is a side-elevational view of a parachute incorporating the present improvement; and

FIG. 2 is an axial cross-sectional view of its canopy.

The parachute shown in the drawing comprises a canopy 1 provided at its center with a relatively large central aperture 2 and a multiplicity of peripheral vents 7 located in a bulging region 3 approximating part of a toroidal surface. The maximum diameter of bulge 3 is somewhat larger than that of the peripheral edge 4 forming the lower boundary of the spread canopy. The intermediate region 6 of the canopy 1 is unperforated in the embodiment illustrated. Shroud lines 5 depend from the canopy 1 in the usual manner.

The vents 7 communicate with the atmosphere outside 15 the convex surface of canopy 1 through respective nozzles 8 which as here shown include annular base flanges 9, frustoconical tubular portions 10 projecting from these flanges outwardly through the vents 7, and substantially cylindrical tubular outer extensions 11 continuing beyond 20 the narrow end of the frustocones. While the extensions 11 could be omitted, their presence has been found to increase the pressure differential along the nozzles and, therefore, the retarding action exerted upon the outflow of air from the concave side of the canopy.

Though the nozzles 8 could be secured to the canopy 1 on either its inner or its outer surface, it is advantageous 30 to mount the flanges 9 on its interior since the nozzles will thereby be held against outward entrainment by the escaping air even if the bond between these flanges and the canopy should fail. Preferably, these nozzles are made of thin and flexible impervious sheet material to facilitate the folding of the parachute, heat-sealable thermoplastics being particularly desirable since in this case the flanges 9 can be thermally fused (e.g. by dielectric heating) to the canopy if the fabric thereof is made of 35 filaments of similar character.

A nozzle 17, generally similar to the nozzles 8, is also shown to overlie the central aperture 2 of the canopy. This aperture can be adjusted with the aid of a cord 18 40 attached to a frustoconical valve plug 19, preferably also of yieldable material such as soft rubber or plastic, which is attached to the frustoconical mouth portion of nozzle 17 through flexible ribs 20 enabling a controlled separation 45 of the two members 17, 19 against the upward pressure exerted by the air which is trapped below the canopy.

The peripheral portion of the canopy adjacent its edge 4 is shown curled up into a piping 14 extending along its inner circumference. A marginal strip 16, forming an 50 integral extension of the curled-up portion 14, is heat-sealed or otherwise bonded to the inner canopy surface above edge 4. An elastic tube 15, e.g. of soft rubber, is shown inserted into the piping 14 to help spread the canopy 1 when the parachute is to be opened. The tube 55 15 need not be inflated for this purpose since its inherent resiliency, coupled with the flexibility of the substantially inextensible sheet material forming the enveloping portion 14, suffices to create an initial entrance gap for the air which thereupon fills the canopy and expands it into the position shown in the drawing.

It will be noted that the entire parachute herein disclosed is made of soft, flexible material and can thus be easily folded, with the tips of the nozzles bent back flat against the canopy to save space.

65 What is claimed is:

1. A parachute comprising a canopy having an exposed outer surface and exhibiting in its expanded state an annular peripheral bulge adjacent its edge with said edge lying inwardly of said bulge, said canopy being provided 70 with a multiplicity of spaced outwardly projecting air nozzles of selectively small cross-section circumferential-

ly distributed over said surface, at least the major part of said nozzles in terms of total effective cross-sectional area being disposed along said peripheral bulge with some of said nozzles being directed upwardly and others of said nozzles being directed downwardly.

2. A parachute comprising a canopy having an exposed outer surface and exhibiting in its expanded state an annular peripheral bulge adjacent its edge with said edge lying inwardly of said bulge, said canopy being provided with a multiplicity of spaced air vents of relatively small cross-section circumferentially distributed over said surface, at least the major part of said vents in terms of total effective cross-sectional area being disposed along said peripheral bulge, each of said vents is provided with a nozzle of progressively reduced cross-sectional area extending outwardly from said canopy.

3. A parachute according to claim 2 wherein said nozzle consists of flexible sheet material.

4. A parachute according to claim 2 wherein said nozzle has an enlarged base secured to said canopy, said base bearing upon the inner surface of said canopy.

5. A parachute according to claim 2 wherein said canopy is provided with a resilient reinforcement of annular configuration extending along said edge.

6. A single-canopy parachute comprising a canopy exhibiting in its expanded state an annular peripheral bulge adjacent its edge, said canopy being provided with a relatively large central air passage and a multiplicity of relatively small outwardly extending air nozzles circumferentially distributed over its surface substantially only in the region of said peripheral bulge with some of said nozzles being directed upwardly and others of said nozzles being directed downwardly.

10
15

7. A single-canopy parachute comprising a canopy exhibiting in its expanded state an annular peripheral bulge adjacent its edge, said canopy being provided with a relatively large central air passage and a multiplicity of relatively small air vents circumferentially distributed over its surface substantially only in the region of said peripheral bulge, each of said vents being provided with a nozzle having a frustoconical tubular portion projecting outwardly from said canopy, said portion having its narrower end remote from the respective vent.

8. A parachute according to claim 7 wherein said nozzle further has a substantially cylindrical tubular portion projecting outwardly beyond said narrower end of said frustoconical portion.

9. A parachute according to claim 7 wherein said air passage is also provided with a nozzle having an upwardly converging portion rising from the top of said canopy.
